UNITED STATES PATENT OFFICE.

WILLIAM H. LE MASSENA, OF GLEN RIDGE, NEW JERSEY.

BOTTLE-COVER HOLDER.

Application filed January 23, 1925. Serial No. 4,143.

To all whom it may concern:

Be it known that I, WILLIAM H. LE MASSENA, a citizen of the United States, residing at Glen Ridge, in the county of Essex 5 and State of New Jersey, have invented certain new and useful Improvements in Bottle-Cover Holders, of which the following is a specification.

My present invention relates to devices by 10 which covers, such as are commonly placed over the tops of milk bottles and similar containers, may be held in place on the bottle. One of the objects of my invention is to provide such a holder which can be readily removed.

My invention will be best understood from the following description and the annexed drawings, in which Fig. 1 shows a well-known type of milk bottle with a cover 20 in place and with one of the embodiments of my invention holding the cover, the cover and holding device being shown in section; Fig. 2 is a plan view of the holder of Fig. 1 before the holder is closed into its holding position; Fig. 3 is a section on the line 3—3 of Fig. 1; Fig. 4 is another embodiment of my invention, with the holder in its open position, and Fig. 5 is another view of the embodiment of Fig. 4, with the 30 holder in its closed position.

Like reference characters indicate like parts in the several views.

For purposes of illustration, I have shown a well-known form of bottle 10 having an 35 enlarged top 11. Such bottles are usually provided with a cap 12 and a cover 13 of paper or the like extending over the top of the bottle and having its skirts extending down below the lower part of the enlargement 11.

Heretofore it has been usual to hold the skirts of the cover 13 against the bottle by means of a wire ring which is made large enough to pass over the top 11 and is then 45 gripped to hold the skirts of the cover 13 against the bottle.

This form of holder, however, is objectionable because it is difficult to remove it, the user ordinarily pressing the holding 50 wire down below the bottom of the skirt of the holder 13 and necessitating the breaking and removal of this wire holder before the bottle is used again.

Moreover, this slipping down of the holder 55 is in some instances difficult, especially if

the holder is pressed tightly against the skirt of the cover.

Instead of the arrangement just described, I provide a continuous metallic ring which is usually circular in plan, with 60 the diameter of this circular portion large enough to permit the ring to be passed over the top of the bottle. The ring is also provided with a portion bent outwardly from the main circular portion in such a 65 way that this bend is the beginning of a fold which may be produced in the ring, which fold is arranged in such manner that the periphery of the generally circular portion will be reduced in length sufficient to 70 draw the wire against the skirt of the cover 13.

Turning now to the embodiment of my invention shown in Figs. 1, 2 and 3, the wire is first formed as shown in Fig. 2, with a 75 generally circular portion 14, a short outwardly bent portion 15 and a longer bent portion 16, the portions 15 and 16 being connected by a rather abrupt bend 17. The holder is slipped over the top of the bottle with the cover 13 in place into the plane of the line 3—3 of Fig. 1. Then, by any appropriate tool, the portion 15 is bent back 80 around the point 18, and this will carry the portion 15 into a fold which will draw the 85 portion 16 in such manner as to shorten the circular portion 14.

If desired, the holder could be opened by grasping the fold 15, 16, as shown in Fig. 3, and rotating it around the point 18, when 90 the parts would be restored more or less approximately to the position shown in Fig. 2, so that the holder could be removed from the bottle or at least readily slipped downward further over the neck of the bottle. 95 Preferably, however, I arrange the holder in such manner that when the fold 15, 16 is bent outward to its initial position, the wire will break at about the point 18, so that the holder will be removed from the 100 bottle.

As a means to this end, I provide the wire of the holder with a slight nick 19 opposite the point 18 and on the outer side of the wire. As the wire is folded from the 105 position of Fig. 2 to that of Fig. 3, the wire will bend around the point 18 without breaking. On the other hand, if the fold 15, 16 is grasped in Fig. 3 and turned counter-clockwise around the point 18, the nick 110

19 will cause the wire to break at 18 after a relatively slight motion is given to the fold 15, 16. Thus the user can readily break and thus remove the holder from the 5 bottle.

It will be understood, of course, that a number of nicks 19 may be applied in the vicinity of the point 18 so as to insure one of them being at the bending point of the 10 wire.

In the arrangement of Fig. 4, I have provided a generally circular portion 20, having an outwardly extending portion comprising a part 21 bent around the point 15 22 and a part 23 bent around the point 24, the parts 21 and 23 being connected by a straight portion 25. As before, a nick 26 may be used opposite the point 22 and a nick 27 opposite the point 24.

20 After the holder of Fig. 4 is in operating position, the points 22 and 24 are carried toward each other by pressure against the parts 21 and 23 with any appropriate tool, thus reducing the periphery of the normally 25 circular portion 20 until it closes on the skirt of the holder 13, the parts 21, 23 and 25 forming a double fold, as shown in Fig. 5.

In this form of my invention, an outward 30 bend of either one of the folds will cause a breakage of the wire at the appropriate nick.

While I have shown the wire which I propose using as circular in cross-section, it 35 will be understood that it may be of any desired cross-section. It will also be understood that while I have shown a holder formed of wire preferably made in a continuous ring by welding the ends together, 40 such continuous ring may be formed by twisting the ends together or by fastening them in any other desired manner, since the method of connecting the ends to form a continuous ring is no part of my present 45 invention.

In the foregoing specification and in the appended claims, I use the word "fold" in its usual meaning of a double or bend in which the parts on either side of the 50 line of bending are brought near together.

It will also be understood that the arrangements which I have shown are merely illustrative and that the embodiment thereof

may be widely varied in form. Thus, while preferably I form a fold in the plane of 55 the ring, this is not essential and some of the advantages of my invention may be obtained by a simple bend instead of a fold.

I claim:

1. A holder for a bottle cover, comprising 60 a continuous ring of metal wire having a bend in the wire with the bent portion making an angle of at least 90° with the ring portion when the ring is drawn into holding position, said wire having a nick in one 65 side thereof at the junction of the bent portion and the ring portion and positioned to be opened when the bend is straightened, whereby the wire will be broken when the bend is restored to its original position before the wire was bent.

2. A holder for a bottle cover, comprising 70 a continuous ring of metal wire having a fold therein in the plane of the ring when the ring is drawn into holding position, the 75 portions of the wire at either side of the point of bending extending substantially parallel with each other and close together, said wire having a nick in one side of the wire at the abrupt bend of the fold, whereby 80 the wire will be broken when the wire is rebent to open the fold.

3. A holder for a bottle cover, comprising 85 a continuous ring of metal wire having a double fold therein when the ring is drawn into holding position, the portions 90 of the wire at either side of the point of bending extending substantially parallel with each other and close together, said 95 folds being adjacent and extending in opposite directions in the plane of the ring and each having a nick in the wire at the abrupt bend in the fold, whereby the wire will be broken when the wire in either fold is rebent to open the fold.

4. A holder for a cover for a bottle having a top larger than the neck to be clasped by the holder, comprising a continuous generally circular ring of metal wire having an internal area large enough to permit the 100 holder to pass over the bottle top, with a part of the wire bent away from the main portion of the ring and a nick in the outside of the wire at the abrupt bend of the fold.

WILLIAM H. LE MASSENA.
